United States Patent Office

Des. 176,220
Patented Nov. 29, 1955

176,220

FLOWER CART

Arthur F. Klingberg, Chicago, Ill.

Application January 24, 1955, Serial No. 34,143

Term of patent 3½ years

(Cl. D35—3)

The figure is a front perspective view of a flower cart showing my new design.

I claim:

The ornamental design for a flower cart, substantially as shown.
